UNITED STATES PATENT OFFICE.

ALVAH C. ROEBUCK, OF WOODSTOCK, ILLINOIS, ASSIGNOR TO WOODSTOCK TYPEWRITER COMPANY, OF WOODSTOCK, ILLINOIS, A CORPORATION OF ILLINOIS.

TYPE-WRITER.

1,250,226.

Specification of Letters Patent. Patented Dec. 18, 1917.

Application filed April 25, 1914. Serial No. 834,553.

To all whom it may concern:

Be it known that I, ALVAH C. ROEBUCK, a citizen of the United States, residing at Woodstock, in the county of McHenry and 5 State of Illinois, have invented certain new and useful Improvements in Type-Writers, of which the following is a specification.

This invention relates to typewriters, and more particularly to the form and construction of the frame, together with the general construction, location, arrangement and method of assembling of the various parts on the frame, and the principal object of the invention is to provide a machine of this 15 class in which the several parts may be assembled on the parts of the frame with the greatest facility and economy of time and a consequent reduction in cost of assembling of the machine as a whole.

20 A further object of the invention is to provide a machine of the class described in which certain of the parts may be assembled on one or more parts of the frame and other parts on other parts of the frame independently of each other, and the several parts of the frame, together with the parts assembled thereon, may be easily and quickly assembled to form a complete machine.

For the attainment of these ends and the 25 accomplishment of other new and useful objects, as will appear, the invention consists in the features of novelty in the construction, combination and arrangement of the several parts generally shown in the accompanying drawings and described in the specification, but more particularly pointed out in the appended claims.

In the drawings, Figure 1 is a perspective view of a typewriter constructed in accordance with the principles of my invention and comprising a top plate and base member of the typewriter but omitting the carriage and certain other parts; Fig. 2 is a view in perspective of the base member together with 45 certain parts assembled thereon; Fig. 3 is a view in perspective of the top plate of a frame in an inverted position with certain of the elements of the typewriter assembled thereon; and Fig. 4 is a side elevation of the 50 machine illustrated in Fig. 1.

A typewriter consists of a great number of different parts, all of which must be assembled, fit accurately and coöperate with other parts. Many of the elements are simi-

lar and all, or nearly all of the separate 60 parts are in themselves quite inexpensive, particularly when made in a considerable quantity. In fact, many of the parts are constructed of sheet material, cut and formed in particular shapes of the desired 65 conformation. One of the greatest expenses, therefore, in the production of a typewriter or other machine of this class is the expense of assembling the various parts and in placing them in the proper coöperative relationship with respect to each other. In machines of this class it is customary to assemble a great many of the parts with the 70 top plate in position on the base frame member, and in fact, many of the frames are 75 made of a sectional construction to facilitate the assembling of the various parts.

In this construction, however, these difficulties are entirely eliminated by providing a simple two-piece frame consisting of a 80 base member 5 and a top plate 6. The machine is assembled by inverting the top plate and securing to it the several elements which make up some of the working parts, and by 85 mounting some of the other parts in the base member 5. With the top plate and base member free from each other the several parts may be assembled and placed in position with the greatest facility, for there is nothing in the way to obstruct the positioning of the parts; it is not necessary when assembling the parts on either the top or the base member of the frame to work on the base member between the two parts of the frame, while the top plate is in position on the base member. They can all be 90 readily seen and conveniently placed in their proper position in both of the frame members, and then after the parts are in their proper places on both the base member and 95 top plate of the frame, the top plate is inverted and placed in position upon the upward extensions of the base member and the several connections are made between the 100 several parts either before or after the top plate is secured in proper position upon the base member.

Referring more particularly to the drawings, the base member 5 is preferably constructed with upward extensions or posts 7 at the corners by means of which the top plate is supported and to which it is secured by suitable fastening means 9. A front ex-

tension 10 of the frame forms a guard for the keyboard, and a cross-piece 11 constitutes a guide for the key-levers.

Mounted in the base member of the frame 5 are type-bar key-levers 12; spacing mechanism comprising a space bar 13 and a link 13^a; carriage shift mechanism comprising carriage shift-keys 14 and a shift-arm 14^a; carriage shift-key locking mechanism 15; a tabulator key 16 with a link 16^a; a line lock key 17 with a link 17^a; and a back-spacer key 17' with an arm 17^b.

The top plate 6 comprises a yoke 18 at the forward edge which preferably rests 15 upon the cross-piece 11, and a lateral depression 19 at each side to permit the free passage of the carriage and carriage shift rail (the former not shown). The upper surface of the yoke 18 preferably forms a 20 rest for type-bars 20 pivoted in a type bar segment 21 secured to the top plate 6.

Mounted on or secured to the top plate 6 are many of the working devices of the machine; the central portion is cut away and 25 forms a space for the free movement of the type-bars. Among the other devices mounted upon the top plate are; the universal bar comprising a reciprocable frame 22 mounted in a rocker 23; a ribbon vibrator 24 with an 30 adjusting device 25 at the forward edge of the plate having connection with the vibrator for varying the path of the typewriter ribbons contained in ribbon spools 26 on the upper side of the plate; tabulator mechanism designated generally by the reference numeral 27 and comprising a link 28; ribbon reverse and feed mechanism comprising a shaft 30, pawls 31 and toothed wheels 32; back-spacer mechanism designated generally by the reference numeral 33 and comprising a lever 34; carriage shift mechanism comprising a pivoted shaft 35 and an end plate forming an abutment 36 secured thereto; line-lock mechanism comprising a link 41 and a signal bell 38, and a carriage motor 39 comprising a thumb-screw 40 for tightening the spring of the motor.

When the various parts or elements of the 50 operating mechanism of the machine are assembled upon their respective parts of the frame, that is upon the top plate or base member of the frame, the top plate is inverted and placed in position on the posts 55 7 of the base frame member 5. With the top plate in this position the co-operating parts on both of the frame members are in such position that they may be readily and easily connected; the carriage shift-arm 14^a 60 bears against the abutment 36; the tabulator arm 28 is secured to the rear end of the key-lever 16; the line-lock release arm 17^a is connected to the line-lock release lever 41; the back-spacer arm 17^b is connected by means 65 of a link 37 (see Fig. 1) to the lever 34; and

the letter space lever is connected by means of the arm 13^a with a bracket 42 on the universal bar frame 22.

In assembling, the type-bar segment 21 is attached to the top plate, as shown in Fig. 3, and after the top plate has been attached to the base member, the type-bars 20 are connected to their corresponding key-levers 12 and pivotally mounted in the segment 21 in any well known manner, as by means of a pivot wire 43.

From this description it will be seen that the parts are readily assembled both upon the base member and upon the top plate member in inverted position, and after the parts are all secured in position upon their respective supporting frame part, the top plate is turned upright, the two frame parts are secured together, and it is necessary only to make a comparatively few connections to place the machine in operation. The assembling is all done with the frame members in their most advantageous position so that all the parts are easily accessible.

It is to be understood that although not all of the parts of a typewriter are named in the description as being assembled upon one part or the other of the frame, enough of them have been named to show the principle of the invention and the advantage to be gained from this construction whereby several of the parts of a mechanism are assembled on one frame element and co-operating parts on another frame element and the two co-operating parts on the separate frame elements are joined when the frame parts are placed in proper position with respect to each other. It is to be understood, of course, that parts not specifically described in the specification are or may be connected to the frame. In general, it may be said that the operating parts are located on one of the frame elements and the actuating parts on the other frame element, the connection of the corresponding operating and actuating parts completing the device as a whole.

This invention is independent of the specific forms of the several devices which compose the typewriter, and it is immaterial, therefore, just what construction is employed. An operative construction is shown but it is possible, of course, to vary this construction without departing from the spirit and scope of the invention. For example, a built up frame, that is, one in which several frame parts are assembled separately to form a two piece frame may have the operating and actuating parts separately assembled on the respective frame parts.

What I claim is:

1. In a typewriter, the combination with a frame comprising a separate and distinct base member and a top plate member adapt-

- ed to be secured thereto, of typewriter operating mechanism adapted to be mounted on and secured to the under side of the top plate member and to be assembled thereon when the top plate is independently inverted, actuating means for the operating parts separately mounted and assembled in the base member, and means to connect the corresponding operating and actuating parts, the top plate being inverted and placed in position on the base member after the operating parts are assembled. 25
2. In a typewriter, the combination with a frame comprising a base member and an independent top plate member, of a type-bar segment, type bar key levers mounted in the base member, type-bars connected to the key levers and pivotally mounted in the type-bar segment, operating mechanism independently mounted on and supported by the top plate, actuating mechanism for said operating devices independently mounted in the base member, means for connecting the corresponding operating and actuating 30
3. In a typewriter, the combination with a frame comprising a top plate member and a base member, of carriage shift, tabulator, letter-space line-lock, and back-spacer operating mechanisms independently secured to and mounted upon the top plate member, 35 separate actuating devices for each of said mechanisms mounted in the base member, and means for connecting the coöperating mechanisms and devices when the top plate is placed in position on the base member. 40

In testimony whereof I have signed my name to this specification, in the presence of two subscribing witnesses, on this 21st day of April A. D. 1914.

ALVAH C. ROEBUCK.
